UNITED STATES PATENT OFFICE.

NORMAN GILES BECKWITH, OF HAMPTON, ENGLAND, ASSIGNOR OF ONE-THIRD TO
WALTER PELMORE, OF HASLEMERE, SURREY COUNTY, ENGLAND, AND ONE-THIRD
TO WALTER MARK NONES, OF LONG ISLAND CITY, NEW YORK.

ROTARY PUMP.

Application filed December 30, 1919, Serial No. 348,373. Renewed June 30, 1922. Serial No. 572,023.

To all whom it may concern:

Be it known that I, NORMAN GILES BECKWITH, a subject of the King of Great Britain and Ireland, and residing at Sheen Cottage, 5 Hampton, in the county of Middlesex, England, have invented certain new and useful Improvements in and Connected with Rotary Pumps, of which the following is a specification.

10 This invention relates to rotary pumps and has for its object to devise an improved form of pump of this nature which will be simple and cheap to manufacture, efficient in operation and of a form such that 15 the wear of the working parts will be reduced to a minimum.

The invention consists in a rotary pump comprising a casing having inlet and outlet orifices, a rotor eccentrically mounted 20 within said casing and means for separating the inlet and outlet sides of the pump.

The invention also consists in other details and arrangements hereinafter described or indicated.

25 The accompanying drawings illustrate one convenient form of pump constructed and arranged in accordance with the invention.

Figure 1 is a sectional elevation, while 30 Figure 2 is a perspective view on a somewhat larger scale illustrating a detail.

In carrying my invention into effect in one convenient manner, I form my pump with a substantially cylindrical casing or 35 chamber *a* mounted if necessary or desirable or a suitable foundation *b* and provided with inlet and outlet passages respectively indicated at *c*, *d*. Within the pump casing I arrange an eccentric *e* on which 40 is loosely mounted a disc or rotary piston *f* so that upon rotation of the eccentric the piston rolls around the inside of the casing *a*. In order to reduce the wear, the piston is preferably provided with a rubber or 45 other resilient tire or tread *g*, while its outer surface may be provided with water sealing grooves *h*, and co-operating with the piston to separate the suction and delivery sides of the pump is a valve *i* which is conveniently located within a recess formed in the pump casing. The valve may be controlled by means of a spring *k*.

In order to guard against excessive pressures within the pump I may provide a

check or relief valve *l* arranged slidably 55 within a chamber *m* forming part of or secured to the pump casing and controlled by adjustable springs *n*, *o*. The chamber *m* is provided with depressions *p* which are arranged on opposite sides of a valve seat 60 *q*. The valve *l* has a central imperforate web portion *r* and laterally extending arms *s*. The arrangement is such that upon an undue rise of pressure on either side of the valve *l* the valve will be forced from its seat over towards the other side by such 65 pressure and the suction and delivery sides of the pump are short-circuited and a bypass established which relieves the pressure.

By means of my invention I have provided a very compact form of pump which is capable of reaching a high efficiency and which is very little liable to wear while at the same time the operation and life of the pump will not be materially affected 75 by the entry of sand, grit or other foreign matter which is usually so detrimental to the action of pumps as hitherto constructed.

Having now described my invention, what I claim as new and desire to secure 80 by Letters Patent is:—

1. A rotary pump comprising a casing having inlet and outlet passages, a pump chamber, a valve and rotary piston chamber communicating with and arranged between said passages having a valve seat and depressions on both sides of said seat, a relief slide valve in said chamber comprising an imperforate central web portion and laterally extending arms, said web portion normally co-acting with said seat to prevent fluid passing from one side of the piston to the other but slidably by abnormal pressure to either side thereof to bring said depressions and spaces between said arms into register and allow fluid to pass from one side of the piston to the other.

2. A rotary pump of the kind defined in claim 1 having its piston circumference covered with elastic material and its ends 100 provided with water sealing grooves therein.

3. A rotary pump of the kind defined by claim 1 in which the relief valve is provided with two coiled springs seated between the oppositely extended arms and bearing against its opposite sides for holding the same normally in closed position.

4. A rotary pump comprising a casing having inlet and outlet passages, a pump chamber with which the passages communicate, a rotary piston mounted in the chamber and a valve cooperating therewith, a relief valve chamber having its ends communicating with said passages and provided with an intermediate valve seat, a relief slide valve in said valve chamber provided with an imperforate portion designed to cooperate with said seat to close communication between the opposite end portions of said valve chamber, said relief valve being slidable by abnormal pressure on either side thereof to displace the relief valve on its seat and permit communication between the opposite end portions of the valve chamber, and resilient means located in the valve chamber and bearing on the opposite sides of said relief valve for normally maintaining the same in position on said seat.

5. A rotary pump comprising a casing having an interior circular wall, a rotary piston therein having a circular periphery, said rotary piston being arranged eccentrically with the circular wall of the casing and contacting with one side of the casing, a yieldable abutment diametrically opposite to the contacting side, an inlet, an outlet, channels communicating with the space between the rotary piston and the casing and with the inlet and outlet, said channels being at right angles to the direction of movement of fluid in the inlet and outlet, a valve chamber, a valve arranged in the valve chamber intermediate its ends and having both of its sides in communication with the said channels, and resilient means bearing against opposite sides of said valve adapted to normally hold said valve in closed position under balanced opposite lateral pressures and normally closing inter-communi-

cation between the said channels and adapted when shifted by unequal pressure 45 against one of the sides of said valve to establish inter-communication between the channels.

6. A rotary pump comprising a casing having inlet and outlet ports, a pump chamber, a rotary piston in the chamber having an elastic circumferential portion and water sealing grooves in its ends, a valve chamber communicating with and arranged between said ports and having a valve seat 50 and depressions on both sides of said seat, a relief slide valve in said chamber comprising an imperforate central web portion and laterally extending arms, said web portion normally co-acting with said seat to prevent fluid passing from one side of the piston to the other but slidable by abnormal pressure to either side thereof to bring said depressions and spaces between said arms into register and allow fluid to pass from 60 one side of the piston to the other.

7. A rotary pump comprising a casing having inlet and outlet ports and a pump chamber, a rotary piston in the chamber, a valve chamber in the casing communicating with and arranged between said ports and having a valve seat and depressions on both sides of said seat, a relief slide valve in said chamber comprising an imperforate central web portion and laterally extending arms, coil springs arranged in the valve chamber at opposite sides of the valve for normally holding said web portions on said seat to prevent fluid passing from one side of the piston to the other side, said valve being slidable by abnormal pressure to either side thereof to bring said depressions and spaces between said arms into register and allow fluid to pass from one side of the piston to the other.

NORMAN GILES BECKWITH.
